R. KELLENDORFER

STARTING SWITCH

Filed Oct. 5, 1923

Inventor
R. Kellendorfer
By Marks & Clark Atty.

UNITED STATES PATENT OFFICE.

RICHARD KELLENDORFER, OF MUNICH, GERMANY.

STARTING SWITCH.

Application filed October 5, 1923. Serial No. 666,799.

To all whom it may concern:

Be it known that I, RICHARD KELLENDORFER, a citizen of Bavaria, Germany, residing at Munich, Germany, have invented 5 certain new and useful Improvements in Starting Switches (for which I have filed application in Germany Oct. 2, 1922), of which the following is a specification.

This invention relates to improvements in 10 electric circuit makers and breakers and more particularly to an improved switch for use in starting electric apparatus.

The starting switch consists of a rocking 15 casing containing a carbon resistance or the like, said casing and cooperating conduits, containing an electricity conducting liquid, which rises on the resistance when the casing is moved to a predetermined position, and thus gradually cuts out the resistance 20 or decreases the latter until the liquid reaches a conductor forming part of the switch. The electric conducting liquid is preferably quick silver.

The switch according to the invention 25 may be employed for starting direct current, alternating current or tri-phase current motors or apparatus, and may be inserted in the circuit of the stator or rotor of a motor.

30 One advantage of the invention is that the shape of the resistance and of the conduits or receptacles for the conducting liquid, may be varied as desired to permit a predetermined manner of starting a particular apparatus or motor.

35 The invention will now be described in detail while referring to the accompanying drawing, in which:

Fig. 1 is a vertical sectional view of a 40 switch constructed in accordance with the invention, while occupying the position which it assumes in making a circuit.

Fig. 2 is a top plan view of the same.

Figs. 3 and 4 are diagrammatic views of 45 the switch, in the circuit of a continuous or direct current motor and a tri-phase induction motor respectively.

The switch comprises a hollow casing 104 carried by a rock shaft 100, supported in a 50 plate 101, and connected, if desired, with a handle to be used in oscillating the casing. The entire switch, in action is preferably rockable through an angle of about 90 degrees, as shown in Fig. 1 by the arrow 102.

55 The casing houses a solid resistance 103, preferably formed of carbon, and this re-

sistance has its lower portion of inverted cone shape and its upper portion of cylindrical shape. The casing 104 is also preferably of cone shape and is spaced from the 60 cone shaped portion of the resistance, so that a conducting fluid 107 may flow down the conduit 105 and rise into the annular chamber 125, when the switch is in the position shown in Fig. 1. The conducting 65 liquid is normally contained in a chamber 106 which communicates with the upper portion of the chamber 125, through a duct 108.

The resistance 103 is insulated from the 70 casing 104 and is fixed in the latter by means of an inverted insulating cup 109 which engages an inverted cup 110 of current conducting material, the latter engaging the head portion of the resistance 103. The conductor 75 110 is provided with a conducting contact 112 which projects into a pocket formed at the lower portion of a vessel 111, which is mounted in insulation at the upper end of the casing 104. Two other contacts 114 and 80 115 project into the vessel 111 and are respectively connected with terminal posts 116 and 117, which are insulated from the casing. The apparatus or motor or parts of these, which is to be started, is arranged between one of said terminal posts and the wire, and such arrangements are diagrammatically 85 shown in Figs. 3 and 4. The vessel 111 is also partly filled with an electric conducting liquid, for instance quick silver. 90

Referring to Fig. 3, it is pointed out that the main wires 118 and 119 are connected to master switches 120 and 121, the latter being connected with a motor, whose field winding 122 is connected in parallel with its rotor- 95 winding 123. The switches 120 and 121 may be of the type automatically actuated by means of the same handle, as is employed to rock my improved switch. The starting switch is shown diagrammatically 100 at 124 and it is interposed between the master switch 121 and the rotor 123.

In Fig. 4 a tri-phase induction motor is illustrated. In this figure the main line wires 37 are connected to master switches 105 35, which in turn are wired with the stator winding 34. The rotor winding (not shown) is connected with three starting switches 1 containing the resistances 2, 3 and 4. Each of these starting switches is 110 of the same general type illustrated in Figs. 1 and 2. These resistances 2, 3 and 4 are

successively cut out by means of the conductor 38. The axle on which the three switches 1 are mounted, preferably also actuates the master switches 35.

- 5 The starting switch constructed as shown in Figs. 1 and 2, operates as follows: When the motor or apparatus is disconnected and the circuit is broken, the starting switch is turned in a clockwise direction about 90 degrees from the position which it occupies in Fig. 1, and at such time the conducting liquid 107 occupies the chamber 106 and there is no conducting liquid in contact with the resistance 103. By tipping or rocking the 10 starter in a counter clockwise direction, to the position shown in Fig. 1, the switch is brought into a position, where the liquid 107 will flow downwardly through the pipe 105 into the lower end of the chamber 125 and gradually this chamber will be filled. As the wall of the casing 104 consists of electric conducting material, the slowly rising liquid in the chamber 125 will complete a circuit through the resistance 103, and this 15 resistance will be gradually decreased until the liquid reaches the lower end of the conductor 110, at which time the resistance will be entirely cut out: At this time the cap 110 is directly connected with the wall 104 by the conducting liquid. From the foregoing it may be seen that this switch first throws in a relatively great resistance, then gradually decreases this resistance, and finally cuts the resistance out altogether. 20
- 25 When the starting switch is turned in the position shown in Fig. 4, the conducting liquid in the vessel 111 flows over the contacts 114, 112 and 115, and first connects the contacts 114 and 112, and at the same 30 time the current is flowing through the cap 110, resistance 103 and the terminal post 117, so that the main line current flows from the post 117 over the contacts 114 and 112, the cap 110, the resistance 103, the liquid in 35 the space 125, to the wall of the receptacle or casing 104, and from this casing to the terminal post 106, which is connected to the apparatus or motor that is to be started. After this, the liquid in the chamber 111 40 flows to the contact 115 and thereby connects the main post 117 and the contact 114 with the contact 115, and the other post 116, which is used in special cases. 45

50 In the arrangement according to Fig. 3, the post 126 is connected to the rotor 123, while the post 116 is connected with the field winding 122. It may be seen that by tipping the switch to the position shown in Fig. 1, the field winding 122 is connected at 55 once with the main line through the liquid in vessel 111 completing the circuit between 117 and 116, while the rotor current increases slowly due to the gradual decreasing of the resistance 103.

60 65 In the diagram shown in Fig. 4, a start-

ing switch is employed, in which the vessel 111 is omitted and the posts 116 and 117 are eliminated. In this case the posts 126 are connected respectively with the ends of the tri-phase rotor-winding, which is connected to slide rings 39, 40 and 41. In this case the resistances 2, 3 and 4 are gradually cut out.

70 The starting switch is tipped by turning the axis 11, whereby the master switches 35 are first thrown in and the stator winding 34 receives at once the full voltage, while the resistances 2, 3 and 4 are slowly thrown out or gradually decreased by the rising of the liquid in the casings 1 of said resistances. 75 When it is desired to disconnect the apparatus or motor, the starting switch is turned 90 degrees in a clockwise direction, and this causes the liquid 107 to flow out of the chamber 125 through the port 108 and pipe 80 105, back into the receptacle 106. At the same time the contacts 115, 112 and 114 are disconnected by the liquid in the vessel 111 flowing toward the right hand end of the latter.

85 90 What I claim and desire to secure by Letters-Patent is:

1. An electric starting switch comprising a casing, a solid resistance arranged in the casing and spaced from the latter, a chamber containing conducting liquid only, and a conduit arranged exteriorly of the space between the casing and resistance and connecting the chamber to the casing, whereby when the casing, resistance, chamber and conduit 100 are tipped, the conducting liquid will flow from the chamber into the casing and gradually decrease said resistance.

105 2. An electric starting switch comprising a casing including a current conducting portion, a resistance extending into the casing and movable with the latter, said resistance being spaced from the wall of the casing, a chamber containing a conducting liquid only, a conduit arranged outside of the space between the casing and resistance and casing, said chamber and conduit being also movable with the casing, whereby the tipping of the parts will cause the conducting liquid to flow from the chamber into the casing and gradually decrease said resistance.

110 115 3. An electric starting switch comprising a rockable casing having an electricity conducting portion adapted to be connected to one wire of the electric circuit, a resistance arranged in the casing, movable with the latter and adapted to be connected to the other wire of an electric circuit, said resistance being spaced from the conducting portion of said casing, a chamber movable with the casing and containing an electric conducting liquid only, and a conduit arranged outside of the space between the casing and resistance and placing the interior of the casing in communication with said chamber.

- ber, whereby when the device is tipped in one direction conducting liquid will flow between the resistance and the conducting portion of said casing and gradually decrease or cut out said resistance, and when the device is tipped in an opposite direction, the conducting liquid will flow from the casing into said chamber. 5
4. An electric starting switch comprising a solid resistance adapted to be connected to one pole of an electric circuit, means for conveying a conducting liquid along said resistance to gradually decrease or cut out the latter when the resistance has been tipped to a predetermined position, said means being adapted to be connected to the other pole of said circuit, conducting liquid storing and conveying means arranged exteriorly of the first mentioned means, movable with the resistance and arranged to feed conducting liquid to the bottom of the first mentioned means, and a port placing the first mentioned means and the storing means in communication at their upper portions. 10
5. An electric starting switch comprising a solid resistance having an inverted cone-shaped lower portion, a casing surrounding the lower portion of the resistance and having a conducting portion, a chamber containing conducting liquid only, and a conduit arranged exteriorly of said casing and connecting said chamber to the lower end of said casing. 15
6. An electric starting switch comprising a rockable resistance, a casing movable with said resistance, having an electricity conducting portion and adapted to convey a conducting liquid along the resistance for gradually cutting the latter out of a circuit, a chamber movable with said casing and containing a conducting liquid, a pipe connecting the chamber to said casing, a vessel movable with said casing and containing a conducting liquid and a plurality of contacts, means connecting one of said contacts electrically to said resistance, and terminal posts connected to the other contacts. 20
7. An electric starting switch comprising a rockable solid resistance, conducting fluid conveying means extending along the resistance and provided with a conducting portion having a terminal post, a chamber movable with said resistance and containing a conducting liquid only, and a conduit ar- 25
- ranged exteriorly of said means and placing said chamber in communication with said means, whereby when the resistance is tipped in one direction the conducting liquid will flow from the chamber into said means and gradually decrease or cut out said resistance. 60
8. An electric starting switch comprising a solid resistance adapted to be rocked about a horizontal axis, a metallic cap at the upper end of said resistance, a contact connected to said cap, conducting liquid conveying means movable with the resistance and arranged to feed conducting liquid along the resistance for gradually decreasing or cutting the latter out and finally bringing the conducting liquid into contact with the cap, a terminal post for said means, a chamber movable with the resistance and containing conducting liquid, 70 and a conduit connecting the chamber to said means, whereby when the resistance is tipped in one direction, conducting liquid will flow from the chamber into said means. 75
9. An electric starting switch comprising a rock shaft, a resistance fixed to said shaft, means movable with the resistance and arranged to convey a conducting liquid along the latter when the rock shaft is moved in one direction, a chamber fixed to the resistance and containing a conducting liquid only, and a conduit arranged exteriorly of said means and connecting said chamber with said means. 80
10. An electric starting switch comprising a casing rockable about a horizontal axis and having an electricity conducting portion adapted to be connected to one pole of an electric circuit, a solid resistance arranged fixedly within the casing and spaced 90 from the electricity conducting portion of the latter, means for connecting said resistance to the other pole of said circuit, a chamber fixed to said casing and containing a conducting liquid only, and a conduit arranged exteriorly of said casing and connecting said chamber to the lower end of said casing, whereby when the casing, resistance and chamber are moved to a certain position, the conducting liquid 95 will flow from the chamber through the conduit and into the casing, and will gradually rise along said resistance and gradually cut the latter out of the circuit. 100
- In testimony whereof I hereunto affix my 110 signature.

RICHARD KELLENDORFER.
